UNITED STATES PATENT OFFICE.

ADOLPH F. LINDGREN, OF BUFFALO, NEW YORK.

LINED SHEET-METAL BARREL.

Application filed June 13, 1923. Serial No. 645,084

To all whom it may concern:

Be it known that I, ADOLPH F. LINDGREN, a citizen of the United States, residing at Buffalo, in the county of Erie and State of New York, have invented a new and useful Improvement in Lined Sheet-Metal Barrels, of which the following is a specification.

This invention relates to a lined sheet metal barrel. As is well known sheet metal barrels as heretofore constructed have been unlined and the use of the same has therefore been limited to such articles which would not be injuriously affected by direct contact with the metal. The absence of a lining therefor excluded the use of sheet metal barrels for use in packing and shipping fruit which by contact with the metal would become stained and also cause the barrel to rust by reason of the moisture in the fruit, while the use of such barrels was also prohibitive for shipping materials which would produce a chemical reaction when coming in contact with the metal.

It is therefore the object of this invention to provide a sheet metal barrel having a protective lining on its inner side which may be constructed either of paper or other suitable material best suited for the particular material or articles which are to be packed, stored or shipped in the sheet metal container.

With this end in view this invention consists generally of providing a sheet metal barrel on its inner side with a protective lining, and specifically with a lining which is co-extensive with the inner surfaces of the sheet metal shell of the barrel or container and which lining is held in place by extending the same into the interlocked parts of the body and heads of the sheet metal shell of the barrel so that this lining is clamped between such parts and reliably held in place while in use.

In the accompanying drawings:

Figure 1 is a blank of the body portions of the shell and lining which are superimposed and have been partly prepared for conversion into the body of the completed barrel, cask or container. Figure 2 is an end view of this blank with the longitudinal edges bent or folded backwardly to form locking hooks thereon. Figure 3 is an edge view of one of the longitudinal edges of the blank showing the opposite ends of the same provided with a double fold for use in fastening the heads to opposite ends of the body

of the barrel. Figure 4 is a perspective view of the body blank rolled or bent into tubular form and having its longitudinal edges locked together. Figure 5 is a longitudinal section, on an enlarged scale, of the completed barrel, cask or container constructed in accordance with my invention. Figure 6 is a fragmentary longitudinal section, on an enlarged scale, of the interlocking joint between an end of the body of the barrel and one of its heads. Figure 7 is a similar view, taken on line 7-7 of Figure 5, and showing the manner in which the longitudinal edges of the barrel body and the locking bar are connected with each other.

Similar characters of reference indicate like parts in the several figures.

As a whole the barrel containing my invention comprises a body of tubular form, and two heads arranged at opposite ends of the body, one of these heads being solid or imperforate, while the other head is provided with an inlet or filling opening which is normally closed by a detachable cover. The strength of the barrel is derived from an outer shell which is constructed of sheet metal and the protection on its inner side is attained by a lining applied to the inner side of the shell.

The body 10 of the shell is constructed of a sheet of metal of the desired character, such for instance as sheet iron, which is provided at its opposite longitudinal edges 90 with notches 11, while this sheet or plate is still in a flat condition, as shown in Figure 1. After this sheet metal blank has been thus notched each of its longitudinal edges is bent or doubled upon itself between the corresponding notches 11 so as to form a hook-shape flange 12 on the outer side of this blank, as shown in Figure 2. The transverse edges of this sheet metal blank are then bent so that a double fold of the metal is produced at each end of the same on the inner side thereof, each of these double folds consisting of a longitudinal intermediate web 13 which is arranged on the inner side of the body portion of the sheet metal shell 105 and is connected at its outer edge with the latter, and an inner hook-shape flange 14 which is spaced apart from the inner side of the corresponding web so as to form a channel therebetween and is connected at its inner edge with the corresponding edge of the web. This web is comparatively wide

while the flange 14 is narrower than the web, for instance the web being twice the width of the flange, as shown in the drawings, whereby the outer edge portion of the web and the corresponding edge portion of the body of the shell project beyond the outer edge of the hook flange 14.

While the body blank of the shell of the barrel is being thus prepared and provided at its edges with single and double folds as above described, a sheet 15 of paper or other suitable protecting material is mounted or arranged on the inner side of the sheet metal body blank of the barrel and subjected to the same notching and folding operations at its several edges so that this body section of the lining is co-extensive with the companion section of the sheet metal shell and covers not only the inner side of the latter with 10 in the boundaries of its edges, but also follows the corresponding inner sides of the several longitudinal single fold hook flanges and also the transverse double folds at opposite transverse ends of the body portion 20 of the shell. Thus, in effect, the body of the barrel consists of two plies of sheet material, an outer ply of sheet metal and an inner ply of paper or other protective material which plies are co-extensive throughout their surfaces and therefore form longitudinal hook-shape portions 16 on the inner side of the longitudinal hooks 12 of the shell, intermediate webs 17 each of which is connected at its outer edge with the lining body and arranged on the inner side of the same, and hook-shaped flanges 18 each of which is arranged on the inner side of one of the webs and connected at its inner edge therewith, said web being comparatively wide and the hook flange narrow, corresponding to the relation of the companion parts of the metal shell.

After the sheet metal and the upper lining constituting the body blank of the barrel have been thus provided with single folds at the opposite longitudinal edges of the same, and with double folds at the opposite transverse or end edges of the same this two-ply blank is rolled or bent into the form of a tube or cylinder so that the double folds of the same are arranged on the inner side of the cylindrical body and the single hook flanges at the opposing longitudinal edges thereof are on the outer side of the body. At this time these two longitudinal hook flanges are opposed to each other but are turned away from each other, and the longitudinal hook portions of the lining are in contact with each other so that only the protective lining is exposed circumferentially on the inner side of the two-ply body of the barrel. At the same time the double folds at the opposite ends of the two-ply barrel body are bent into circular form.

The two longitudinal hook-shape flanges 12

of the barrel body are drawn together so as to hold the protective lining on these parts of the shell firmly in engagement with each other by means of a locking bar which preferably consists of a sheet metal web 19 adapted to engage with the outer sides of the lined hooks 12 of the shell and provided at its opposite longitudinal edges with hook flanges 20 which are turned toward each other on the inner side of the web 19 and engage with the channels formed between the hook flanges 12 and the body portion 10 of the shell, as shown in Figures 4 and 7, whereby the longitudinal joint in the barrel is closed firmly and rendered leak tight.

The lower and upper heads of the shell of the barrel are made of sheet metal in the form of disks 21 and 22, each of these disks being provided at its peripheral edge with an outwardly projecting circumferential web 23 which is connected at its inner edge with the respective head disk, and a hook-shaped flange 24 surrounding the web 23 but separated therefrom by an intervening circumferential channel and connected at its outer edge with the corresponding edge of the web 23, as best shown in Figure 6. On its inner side and co-extensive with the disk, web and flange of each head is arranged the head section of the protective lining of paper or the like for this part of the barrel shell, which protective section comprises a central disk 25 engaging with the inner side of the disk of the corresponding head, a web 26 projecting outwardly from the margin of the disk 25 and connected at its inner edge therewith, and a flange 27 surrounding the web 26 and connected at its outer edge therewith, but separated therefrom by an intervening annular space. The lining section for each head is applied thereto while these parts are still in a flat condition and in effect form two plies of head material and thereafter these two plies are bent simultaneously into the shape described so that they are co-extensive throughout their areas. After the heads have been thus formed of two plies of material each, an outer ply or section of sheet metal, and an inner ply of protective material, such as paper, the heads and body of the barrel are assembled by engaging the peripheral flange of each head with one of the circumferential channels formed at one end of the barrel body between the web and hook flange at the corresponding end of the body, and simultaneously engaging the hook flange at this end of the body with the annular channel formed between the hook flange and web of the respective head of the barrel. When the parts are thus assembled the hook portion 18 of the lining of the body engages with the web portion 26 of the lining of the respective head, as shown in Figures 5 and 6 so that these parts of the metal surfaces of the locking joint between

the head and the body are completely covered with protective lining and no metal surfaces are exposed or accessible to the material which is contained within the receptacle.

After the heads and body of the barrel have been thus assembled these heads are securely held in place on the body by bending inwardly the outer portions of the webs

10 13 and the adjacent portions of the body 10 of the shell and the corresponding parts of the lining therein, so that these inwardly turned parts overhang and engage with the outer ends of the hook flanges and webs of 15 the barrel heads, as shown in Figures 5 and 6 and securely unite these parts so that they will not come apart when subjected to use.

The filling opening is formed in the central part of the upper head and in order to 20 provide a good seat in the same for the cover which closes the barrel and also to permit of lining this part of the barrel so as to cover up the internal metal surfaces of the same an outwardly curled bead 28 is formed on

25 the metal disk of this head and the adjacent part of the protective lining of this head is also turned outwardly and around this bead in the form of a curled flange or bead, as shown at 29, in Figure 5.

30 Although the cover for this filling opening may be variously constructed the same, as shown in Figure 5, comprises an outer section of sheet metal and an inner section of protective lining, the two plies of which

35 are co-extensive as to area so that no part of the inner surface of the metal section of this cover is exposed on the interior of the receptacle or barrel. The outer section of the cover is stamped out of sheet metal so

40 that it is downwardly dished and forms a side wall 30, a flat inner crown 31 connected with the inner edge of the side wall and a laterally projecting annular rim 32 arranged at the outer edge of the side wall 30. The

45 inner section of this cover which forms the protective lining therefor is constructed of paper or similar material so as to form an inner flat crown 33 arranged on the inner side of the crown 31 of the metal section of the cover, a side wall 34 extending along the corresponding inner side of the wall of the metal cover section, and a laterally projecting rim or flange 35 arranged on the inner side of the flange or rim 32 of the metal

50 cover section. When in use the inwardly dished part of the two-ply cover is inserted in the filling opening of the perforated head of the barrel so that the wall portion of the protective lining on the cover engages with

55 the outwardly curled bead portion 29 of the protective lining on the perforated head of the barrel, as shown in Figure 5, thereby forming not only a tight joint between the cover and the perforated head but also pre-

60 the outwardly curled bead portion 29 of the protective lining on the perforated head of the barrel, as shown in Figure 5, thereby forming not only a tight joint between the cover and the perforated head but also pre-

65 venting contact of the contents of the bar-

rel with any of the metal surfaces of the cover or the adjacent head. After the barrel has been filled with the desired material and the cover has been introduced into the filling opening of the same, this cover may 70 be held in place by any suitable or approved means, for instance, this may be accomplished by swelling the lower part of the side wall of the cover, as shown at 36, together with the adjacent part of the lining 75 thereon so as to form an outwardly facing shoulder or bead on the wall of this cover which abuts against the inner side of the edge portion of the filling opening of the 80 perforated barrel head and prevent the cover from being withdrawn by ordinary means, but instead requires the head to be destroyed before it can be removed as is customary in this class of covers.

If desired the body of the barrel may be 85 strengthened by forming circumferential re-inforcing heads or corrugations 37 thereon in a manner common to this type of barrel.

A barrel, keg or container constructed in 90 accordance with this invention cannot only be manufactured at low cost, but it also holds the protective lining securely against displacement on the inner side of the metal shell and insures a complete coverage of the 95 metal surfaces by means of the protective lining so that any materials packed therein will be protected against contamination or injury or chemical reaction.

I claim as my invention:

1. A barrel comprising an outer shell of sheet metal having a tubular body and heads arranged at the ends of said body, said body provided at each end with a double fold consisting of a web arranged within the body and connected at its outer edge therewith, and a flange arranged within the web and connected at its inner edge with the corresponding edge of the web but separated therefrom by an intervening outwardly opening channel, and each head having at its margin an inwardly projecting flange which engages with the channel of said double fold, and a protecting lining having a tubular body section arranged within the body of the shell and having parts following the corresponding surface of its double folds, and head sections arranged on the inner side of said shell heads and having parts following the flanges thereof, whereby the edge portions of the lining are clamped between the interlocking parts of said shell body and heads and are held in place thereby.

2. A barrel comprising an outer shell of sheet metal having a tubular body and heads arranged at the ends of said body, said body provided at each end with a double fold consisting of a web arranged within the body and connecting at its outer edge there-

4. A barrel comprising an outer shell of sheet metal having a tubular body and heads arranged at the ends of said body, said body provided at each end with a double fold consisting of a web arranged within the body and connected at its outer edge therewith and a flange arranged within the web and connected at its inner edge with the corresponding edge of the web but separated therefrom by an intervening outwardly opening channel, said web being wider than said flange, and each head having at its margin an inwardly projecting flange which engages with the channel of said double fold, the outer part of each web and the adjacent part of the shell body being bent inwardly over the adjacent part of the corresponding shell head, and a protecting lining having a tubular body section arranged within the body of the shell and having parts following the corresponding surface of its double folds, and head sections arranged on the inner side of said shell heads and having parts following the flanges thereof, whereby the edge portions 20 of the lining are clamped between the interlocking parts of said shell body and heads and are held in place thereby.

3. A barrel comprising an outer shell of sheet metal having a tubular body and heads arranged at the ends of said body, said body provided at each end with a double fold consisting of a web arranged within the body and connected at its outer edge therewith, and a flange arranged within the web and connected at its inner edge with the corresponding edge of the web but separated therefrom by an intervening outwardly opening channel, and each head provided at its margin with an outwardly projecting web and a flange arranged around said head web and having its outer edge connected with the corresponding edge of the head web, and separated therefrom by an intervening inwardly opening channel, and a protecting lining consisting of a body section engaging with the inner side of the shell body and following the corresponding side of its double folds, and a head lining section engaging with the inner side of each shell head and following the corresponding sides of its web and flange, the flange at each end of the shell body and the adjacent part of its lining engaging with the inwardly opening channel of the adjacent head and its lining, and the flange of each head and the adjacent part of its lining engaging with the outwardly opening channel of the corresponding end of the shell body and its lining.

5. A barrel comprising a shell of sheet metal, and having a head containing a filling opening the edge of which is provided with an outwardly curled bead and a protecting lining arranged on the inner side of said shell and the inner side of said bead.

6. A barrel comprising a shell of sheet metal and having a head containing a filling opening the edge of which is provided with an outwardly curled bead, a cover of sheet metal having an inwardly dished central part fitting into said filling opening and having a marginal rim arranged above said head, and a protecting lining arranged on the inner side of said cover and following the dished part and the rim thereof so that the lining of the cover engages the lining of said head.

In testimony whereof I hereunto affix my signature.

ADOLPH F. LINDGREN.
